Design U.S. Appl. No. 29/482,279, filed Feb. 17, 2014.

Primary Examiner — Robert M Spear*Assistant Examiner* — Eliza Bennett-Hattan*74) Attorney, Agent, or Firm* — Polsinelli PC(57) **CLAIM**

The ornamental design for the metal profile for switchgear cabinets, as shown and described.

DESCRIPTION

FIG. 1 is a perspective front view of the first embodiment of the metal profile for switchgear cabinets;

FIG. 2 is a perspective back view of the first embodiment of the metal profile for switchgear cabinets;

FIG. 3 is a back view of the first embodiment of the metal profile for switchgear cabinets;

FIG. 4 is a front view of the first embodiment of the metal profile for switchgear cabinets;

FIG. 5 is a side view of the first embodiment of the metal profile for switchgear cabinets;

FIG. 6 is a top view of the first embodiment of the metal profile for switchgear cabinets;

FIG. 7 is a perspective front view of the second embodiment of the metal profile for switchgear cabinets;

FIG. 8 is a perspective back view of the second embodiment of the metal profile for switchgear cabinets;

FIG. 9 is a front view of the second embodiment of the metal profile for switchgear cabinets;

FIG. 10 is a back view of the second embodiment of the metal profile for switchgear cabinets;

FIG. 11 is a side view of the second embodiment of the metal profile for switchgear cabinets; and,

FIG. 12 is a top view of the second embodiment of the metal profile for switchgear cabinets.

The metal profile for switchgear cabinets is shown with a symbolic break in its length. The appearance of any portion of the article beyond the break lines forms no part of the claimed design.
